UNITED STATES PATENT OFFICE.

EDGAR H. FREEMAN, OF TRENTON, NEW JERSEY, ASSIGNOR TO E. H. FREEMAN ELECTRIC COMPANY, A CORPORATION OF NEW JERSEY.

LAMP-LOCKING CONSTRUCTION.

1,326,924.

Specification of Letters Patent.

Patented Jan. 6, 1920.

Application filed July 2, 1918. Serial No. 243,008.

To all whom it may concern:

Be it known that I, EDGAR H. FREEMAN, citizen of the United States, residing at Trenton, in the county of Mercer and State 5 of New Jersey, have invented certain new and useful Improvements in Lamp-Locking Constructions, of which the following is a specification.

This invention relates to a novel and 10 practical lamp locking construction for effectually locking electrical lamps in their sockets or receptacles.

To this end the invention contemplates a 15 socket construction involving means for securely locking the plug of a lamp therein, thereby preventing theft or removal by unauthorized persons, or the removal of the lamp a sufficient distance to draw it away from its center plug contact to thereby open 20 the circuit. In this connection it is proposed to provide a locking mechanism which is entirely concealed, and so embodied in the socket construction, that it is in effect a part thereof, whereby in order to destroy the locking 25 means for the lamp it would be necessary to destroy the entire socket.

A further object of the invention is to provide a lamp locking construction which though protected against unauthorized 30 agencies may nevertheless be readily manipulated by authorized persons to lock and unlock the lamp without injury to the lamp or other part of the device.

A further object of the invention is to 35 provide a construction of the character referred to which is simple, practical, and reliable, and susceptible of embodiment in any of the well known forms or types of electrical lamp sockets. A more general object 40 of the invention is to provide a lamp locking device which may be readily incorporated in the construction of an electrical fitting such as sockets and electrical receptacles adapted to carry the ordinary electrical 45 lamp.

With the above and other objects in view the invention consists in the novel construction, combination and arrangement of parts hereinafter more fully pointed out, illustrated and claimed.

A preferred and practical embodiment of the invention is shown in the accompanying drawings, in which:

Figure 1 is a top plan view of an all-por-

celain type of socket having the present invention embodied therein. 55

Fig. 2 is a vertical sectional view taken on the line A—A of Fig. 1.

Fig. 3 is another cross section taken on the line B—B of Fig. 1. 60

Fig. 4 is a detail elevation of the screw shell portion of the socket and the shiftable clamping bolt of the locking construction.

Fig. 5 is a detail perspective view of the locking post and snubbing coil which grips 65 the lamp plug.

Fig. 6 is a detail perspective view of the locking bolt.

Similar reference characters designate 70 corresponding parts throughout the several figures of the drawings.

As previously indicated, the present invention may be carried out in connection with various types or forms of electrical lamp holders. However, for the purpose 75 of illustration, there is shown in the drawings, a lamp receptacle of the all-porcelain type, which preferably includes an attaching base 1, and the socket portion 2 for receiving the screw plug of the incandescent 80 lamp. This socket portion 2, while of a generally circular formation, is provided at one side with an offset angular portion 3 which forms a housing chamber 4 for the operating parts of the lamp locking means, and has in 85 one of its side walls a key-hole opening 5, for the purpose to be explained.

The metal fittings for the receptacle or socket, may be, and preferably are, conventional and according to the usual practice. 90 Moreover, the present invention includes as one of its important and practical features the use of the screw shell contact as a support and guide for the main locking member of the device as will presently appear. 95 Accordingly, the socket 2, accommodates therein both lamp terminals, namely, the center plug contact 6 connected with one binding contact 6^a and the screw shell contact 7 connected with the other wire binding 100 terminal 7^a.

As indicated the screw contact shell 7 combines with the locking device to readily engage and lock the plug of the lamp in the socket. Therefore, to this end, it is proposed 105 to employ within the mouth of the screw shell contact a plug locking member which is preferably in the form of a helically coiled

spring wire, which is so arranged and disposed in the screw shell that under the manipulation of the operating parts housed within the chamber 4, the same will have the effect of a snubbing coil on the lamp plug to thereby securely lock the plug in the socket.

Referring to this snubbing coil which is designated generally as 8 it will be observed that the same consists of a relatively few but spaced convolutions, the same being of a sufficient number however to give a firm frictional clamping engagement on the entire circumference of the plug, and when in position the said convolutions seat themselves in the valleys of the threads of the screw shell to thus permit of the free insertion of the lamp plug. One end of the so-called snubbing or locking coil 8 is preferably rigidly secured to the interior of the shell 7 as indicated at 9, Fig. 3, by soldering or otherwise while the other end is adapted to project into a suitable transverse slot 10 formed in a locking post designated generally as 11 and arranged within the housing chamber 4 of the socket exterior. It will thus be apparent that one end of the coil 8 is held fast and rigid to the shell while the other end is relatively free, whereby under the manipulation of the operating mechanism, presently to be described, it may be contracted and expanded to effect the locking and the removal of the lamp in the socket. An important feature in connection with the foregoing is that the screw shell contact which acts to hold the convolutions of the coil in a proper spaced relation, thereby prevents the convolutions of the coil kicking out of their proper spiral planes, and thus permits a proper threading in and out of the lamp plug. At the same time, being only secured at its innermost end, the threads of the screw shell contact do not interfere with the free contraction and expansion of each individual coil throughout its entire extent.

The locking post 11 above referred to is preferably in the form of an angular plate having the transverse slot 10 in one wall while the opposite wall is provided with a locking bolt opening 12. One end of the post is also formed with an offset holding portion 13 which is adapted to be held in place by one of the screws for a binding terminal, as is clearly shown in Fig. 2, while the upper end of the post 14 is bent over to provide a substantially closed end wall for sealing the entire housing chamber 4, which will prevent tampering with the means for manipulating the snubbing coil. As will be readily observed from Fig. 1, the locking post 11 which occupies a rigid and fixed location in the socket readily accommodates within its angle portion a suitable shiftable locking nut of angular form, the same being

designated generally as 15 and having the flange thereof disposed adjacent the slot 10 adapted to receive the free end of the snubbing coil 8, while the opposite flange of the nut is provided with a screw threaded opening 16 for receiving an operating bolt or screw 17 which has a loose fit in the opening 12 of the post 11.

The locking bolt or screw 17 is clearly shown in Fig. 6 of the drawings and preferably consists of a threaded shank portion for engaging the threaded opening 16 of the nut 15, and a special head portion 18 having formed therein a suitable transverse slot 19 and a centrally projecting pin 20, whereby the complementary parts 20^a of a key K may be readily engaged therewith to give the same the necessary rotary movement to cause the shifting of the nut 15. For the purpose of preventing the operation of the screw 17 with unauthorized tools or keys, the head thereof is preferably protected by a suitable housing cup 21, clearly shown in Figs. 1 and 4 of the drawings.

With the arrangement described, it will be apparent that since one end of the coil 8 is rigidly held within the screw contact 7, and the free end thereof is connected with the shiftable nut element 15, the movement of the latter through the operation of the screw 17 will readily cause the contraction or expansion of all of the convolutions of the coil, according to the direction of rotation of the screw. The normal condition of parts is shown in Fig. 1, wherein the snubbing coil is expanded as much as the screw shell will permit, and the movable end of the said coil 8 occupies a position at one end of the slot 10. When the screw 17 is turned to the right by means of the key, it will have the effect of bringing the nut element 15 forwardly as indicated by dotted lines in Fig. 1 which will thus contract or reduce the diameter of the coil and thus cause the same to have an extremely tight binding or locking engagement with the plug of the lamp which may be inserted therein.

It will now be apparent that the present arrangement provides a simple and effective locking mechanism which may be readily manipulated by authorized persons, and which is relatively small and easy to make and assemble, thus presenting practical advantages which greatly enhance the commercial value of the invention. Furthermore, by utilizing the coil 8 in the manner described any desired pressure may be placed upon the plug of the lamp without danger of breaking or rupturing any part of the lamp so that if it is desired to remove the same, it may be still available for further use.

I claim:

1. A lamp locking device comprising, in combination with the socket member, a heli-

- cal snubbing coil arranged within the socket member, a coil holder and guide within the socket member, and a key actuated operating device operatively engaging the coil to contract and expand the same. 5
2. A lamp locking device comprising, in combination with the socket member, a helical snubbing coil arranged within the socket member, a screw shell contact located within the socket member and constituting a holder and guide for the snubbing coil, and a key actuated operating device operatively engaging the coil to contract and expand the same. 10
3. A lamp locking device comprising, in combination with the socket member, a helical snubbing coil arranged within the socket member, a screw shell contact located within the socket member and constituting a holder and guide for the snubbing coil, and a key actuated operating device operatively connected with one end of the coil to contract and expand the same. 15
4. A lamp locking device comprising, in combination with the socket member, a helical snubbing coil arranged within the mouth of the socket member, a coil holder and guide within the socket member, and a key actuated operating device engaging with one end of the coil only to contract and expand the same. 20
5. A lamp locking construction for electrical lamp sockets including in combination with the screw shell contact of the socket, of a convoluted spring member arranged in the mouth of said shell and having one end fastened therein while the other end is free, and a device for moving the free end of said member, said device 25
- consisting of a fixed slotted post for receiving the free end of the spring, a shiftable nut element, and a rotatable screw loosely abutting against said post and having a threaded engagement with said shiftable nut element. 40
6. A lamp locking construction for electrical lamp sockets including in combination a socket body having a housing chamber at one side of the socket portion thereof, and a key-hole opening in the wall of said housing chamber, a screw shell contact within the socket of the body, a contractible coiled locking element arranged within the mouth of the screw shell contact, an operating device for said locking element arranged within the housing and including a key-operated locking screw and a shiftable nut engaged with said locking element. 45
7. A lamp locking construction for electrical lamp sockets including in combination a socket body having a housing chamber at one side of the socket portion thereof, and a key-hole opening in the wall of said housing chamber, a screw shell contact within the socket of the body, a contractible coiled locking element arranged within the mouth of the screw shell contact, an operating device for said locking element including a keeper post having one end thereof bent over to form a seal for the housing chamber, and means also carried by said post for manipulating the locking element. 50
